(57) **CLAIM**

The ornamental design for a fawn feeder, as shown and described.

DESCRIPTION

All the material from the related applications which is essential to the claimed design is included in this application. Any material in the related applications which is not present in this application forms no part of the claimed design.

FIG. 1 is a perspective view of a fawn feeder according to my new design;

FIG. 2 is a left side elevation view of the fawn feeder shown in FIG. 1;

FIG. 3 is a right side elevation view of the fawn feeder shown in FIG. 1;

FIG. 4 is a front elevation view of the fawn feeder shown in FIG. 1;

FIG. 5 is a rear elevation view of the fawn feeder shown in FIG. 1;

FIG. 6 is a top plan view of the fawn feeder shown in FIG. 1; and,

FIG. 7 is a bottom plan view of the fawn feeder shown in FIG. 1.

The broken lines are for illustrative purposes only and form no part of the claimed design. The stem pipe is shown in a broken away style for ease of illustration since the stem pipe's length is not fixed.
